UNITED STATES PATENT OFFICE.

CHARLES ERNEST SCHWARTZ, OF CARTHAGE, MISSOURI.

SCRAP-BOOK.

SPECIFICATION forming part of Letters Patent No. 645,191, dated March 18, 1900.

Application filed August 8, 1899. Serial No. 726,559. (No model.)

To all whom it may concern:

Be it known that I, CHARLES ERNEST SCHWARTZ, a citizen of the United States, residing at Carthage, in the county of Jasper 5 and State of Missouri, have invented a new and useful Scrap-Book, of which the following is a specification.

This invention relates to an improvement in scrap-books and indexes; and the object of 10 the same is to provide a book of this character which when used as a scrap-book will dispense with the time and labor involved in pasting clippings therein and permit the latter to be read from both sides or to be reclassified or changed at any time desired and wherein a greater number of the clippings can be placed on each page than is possible in the ordinary scrap-book; further, to use the same device for applying clippings to single sheets 15 or portfolios of paper which may be filed in boxes and from which the clippings may be removed at any time to scrap-books; furthermore, to arrange for a series of indexes by the use of the same holding device that is 20 employed to retain the clippings in place or to employ said holding devices alone as index-slips which are capable of quick change and readjustment and easily brought up to date, all of which may be acquired without defacing 25 the scrap-book, even if the said holding devices are entirely removed subsequent to their use in the book; furthermore, to use the holding devices for the clippings as means to contain titles and also to immediately retain the 30 clippings of a length greater than that of the page or leaf to which they are applied.

With this end in view the invention consists of stiff paper leaves either bound in a scrap-book or left in the form of portfolios or 35 single sheets with parallel lines of holes or apertures running longitudinally thereof and adapted to receive holders consisting of small strips of cardboard or other suitable material cut with projecting ends adapted to be removably introduced into the holes and in some instances having a portion of their width gummed or supplied with adhesive material and the upper part left clear for the reception 45 of the heading or other desired information 50 in connection with the clippings, and when used for indexing said strips will be entirely

free of adhesive material and likewise arranged in the holes in succession in accord with the alphabetical arrangement of the name or other matter and susceptible of removal or rearrangement. 55

The invention further consists in the details of construction and arrangement of the several parts, which will be more fully hereinafter described and claimed. 60

In the accompanying drawings, Figure 1 is a perspective view of a scrap-book embodying the invention and shown open. Fig. 2 is a longitudinal vertical section of one of the scrap-book leaves. Fig. 3 is a transverse vertical section of one of the leaves. Fig. 4 is a detail perspective view of one of the holders. Fig. 5 is a similar view of one of the holders without the adhesive or gummed surface and adapted for indexing or simple holding 70 service. 65

Similar numerals of reference are employed to indicate corresponding parts in the several views.

The numeral 1 designates a book-back of 75 any preferred dimension and ornamentation and having bound therein a series of leaves 2, which will depend as to number upon the size of the book and have considerable space between them to compensate for the thickness 80 of the clippings that may be applied thereto. Each leaf has a series of openings or apertures 3 cut therethrough and arranged in longitudinal alinement, being a distance apart about equal to or approximating the width of 85 a newspaper or periodical column. This dimension, however, may be changed at will, and the number of openings or apertures 3 varied in accordance with the nature of the clippings or the matter to be stored in the 90 book. As shown, the parallel lines of openings or apertures 3 are intended to accommodate three newspaper or periodical columns, and in transverse direction the said openings or apertures are also in alinement and convenient for a straight arrangement of the clippings. The clippings are held in the book and on the page or leaf by means of holders 4, consisting, preferably, of strips of cardboard cut with projecting reduced ends 5, which are 95 introduced into the openings or apertures 3. The opposite reduced ends 5 of the holders 100

can be easily slipped into the openings or apertures in the leaves of the book, and at the point of conjunction of the said reduced ends with the body of the holder opposite 5 stop-shoulders 6 are formed which bear against the parts of the leaf around the said openings or apertures. The distance between the shoulders 6 longitudinally of the holders is equal to the interval in a transverse direction 10 between the openings or apertures 3 on opposite sides of a space leaf approximating the width of a newspaper or periodical column. Of course when these openings or apertures 3 are arranged at a greater distance 15 apart to accommodate larger clippings or scraps the holders will be similarly elongated and otherwise properly proportioned. When the holders are used to attach clippings, they have a layer or covering of gum or adhesive 20 material 7 applied on one side near what is to serve as the bottom edge, the surface 8 of the holder immediately above the said gummed surface being left clear for the application of a date, name, or title, or such information as can be applied thereto and desired to be written in connection with the clipping. 25

The clipping is fastened to the holder by the layer or covering of gum or adhesive substance and is permitted to drop down over the page after the reduced ends 5 are inserted in two of the openings or apertures 3. It will be observed that by this means both sides of the clipping or other matter are left free for 35 ready inspection, and the holders bearing the clippings are arranged in succession regularly in the same manner toward the bottom or foot of the page.

In arranging the holders in the pages, as 40 stated, the clippings from the upper end toward the foot of each page rest successively on top of each other, so that they may be easily turned up to read others that may be under the same. When a clipping is extraordinarily long or of greater length than the 45 distance between the point of application of the holder carrying the same and the bottom or foot of the page, such clipping is tucked up or folded, as shown by Fig. 1, at 99, and the 50 tucked-up part is retained by a holder similar to that shown by Fig. 5 and without the adhesive material thereon. This will provide for a compact arrangement of the clippings and also avoid the projection of the 55 ends of the same at the bottom edge of the page.

The pages will be numbered successively, and at the front of the book an index can be 60 conveniently arranged by the use of the holders illustrated by Fig. 5 and have written or imprinted thereupon classification titles or headings or similar matter and the page in the book where they are located. These index-holders will be arranged in regular order and 65 preferably in alphabetical sequence, and at any time desired a rearrangement, replacement, or entire withdrawal may ensue in ac-

cord with the removal from the application to the book of the clippings. These holders may also serve alone as index mediums for 70 general purposes and overcome the necessity of redisposition of long complex indexes by the addition thereto or subtraction therefrom and a recast on the same as is now ordinarily carried on. 75

The present form of the scrap-book avoids the inconvenience arising from the methods now commonly in vogue of applying clippings or other matter to a scrap-book and also permits the clippings to be removed without destroying the same or marring the book. This makes possible the elimination of dead material and an easy means of reclassifying the clippings by removing any single one or a number from one page to another. 80

The improved manner of applying the clipping will be found very convenient in what are known as the "clipping-bureaus," and instead of applying the clippings to slips of paper showing the name and date of the newspaper or periodical from which each one was clipped, as is now done by the bureaus, they may be applied directly to the cardboard holders of a character illustrated by Fig. 4, the upper part of the holder being used to 95 bear the same information which is now written or stamped on the aforesaid paper slips and sent to the subscribers in this condition. In this case the holders may be placed by the subscriber at will in his scrap-book or clipping-file, and he would be saved the time and labor which are now required to paste these clippings in scrap-books or on sheets of paper and to write under each one its source of publication. 100

Innumerable other uses and advantages will appear from time to time. The adaptability of the improved arrangement is general, and it will facilitate the collection and storage or rearrangement of the clippings or 110 other matter adapted to be retained in regular order. 105

Changes in the proportion, size, form, and minor details of construction may be resorted to without in the least departing from the 115 spirit of the invention or sacrificing any of the advantages thereof.

Having thus described the invention, what is claimed as new is—

1. In a book, the combination of a number 120 of leaves, having parallel lines of openings therein, and holders adapted to contain reference matter, having reduced ends removably inserted in the said openings.

2. In a book, the combination of a number 125 of leaves having a series of lines of openings therethrough, arranged in parallel relation and holders having opposite ends removably fitted in the said openings, to which clippings are fastened, whereby the said clippings may 130 be removed and withdrawn or their positions changed within the book.

3. The combination with a book having the leaves with a series of openings therein, ar-

ranged in parallel lines, of holders having opposite reduced ends to removably engage the said openings, the length of the holders longitudinally between the points of conjunction of the reduced ends therewith being equal to the distance between the openings.

4. The combination with a book having a series of leaves with openings therethrough, arranged in parallel lines, of a holder having opposite reduced ends to removably engage a part of said openings and also provided with an adhesive substance on a portion thereof, to which is secured a clipping or other matter and another holder similarly mounted in other openings and adapted to hold a folded or

tucked up portion of the clipping carried by the first-mentioned holder.

5. The combination with a leaf having lines of openings therein, arranged in parallel relation, of holders having opposite reduced ends to engage the said openings and having applied to the surface of one side thereof a covering of adhesive substance.

In testimony that I claim the foregoing as my own I have hereto affixed my signature in the presence of two witnesses.

CHARLES ERNEST SCHWARTZ.
